UNITED STATES PATENT OFFICE.

HERMANN SCHÖPS, OF BERLIN, GERMANY.

ROCKING CHAIR.

Application filed August 26, 1922. Serial No. 584,594.

To all whom it may concern:

Be it known that I, HERMANN SCHÖPS, a citizen of Germany, and residing at Unterstrasse, 1, Neukolln, Berlin, Germany, have invented a new and useful Improvement in a Rocking Chair, of which the following is a full, clear, and exact specification, reference being had therein to the accompanying drawing.

10 The invention relates to a rocking chair, the seat of which rests upon a support in such a manner as to permit of being easily swung and which with the help of a lever arrangement connected with the supporting 15 frame can be easily set into swinging motion. The person seated on the chair can without effort merely by movement of the foot, bring the chair to rock backwards and forwards and on the other hand by leaning 20 forward and at the same time drawing in the legs cause an immediate cessation of the motion, for instance, for purpose of leaving the chair.

On account of the easy motion of the rocking chair it is possible to connect appliances 25 causing a motion of the air with the same, so that at the same time a cooling effect is produced, which renders the use of this chair in warm seasons and in the Tropics, etc., particularly agreeable.

In order to adapt the chair for ready use by persons of various sizes, the point of contact of the chair seat with the supporting point is adjustable by means of a simple 35 gearing, so that the person seated on the chair can himself by a simple turn of the crank adjust the position of the chair in accordance with his size. After corresponding adjustment, the slightest change in the 40 position of the legs causes a change in the position of the seat or a swinging of the chair, thus producing the pleasant rocking movement. In every position of the supporting point, which for practical purposes 45 should be movable upon rollers, the chair can be completely tilted backwards to serve as full length resting chair, or it can be raised to serve as a sitting chair.

If the chair is completely tilted backwards 50 the lower part of the legs and the knees are stretched out and are supported by the foot rests so that the legs also can be brought into a resting position. If a person lying in this position desires to 55 quickly leave the chair, it is not necessary to turn back the supporting point, since the

chair, due to the lever arrangement in connection with the foot rest, is equi-poise, it is merely necessary to draw in the legs whereby the foot rest and the levers connected therewith exercise a greater pressure which brings the chair into sitting position. The person simultaneously raising his body, can now leave the chair, which remains in upright position, since the front parts of the frame are heavier than the rear part.

One form of application of the object of this invention is shown in the drawing in which

Fig. 1 is a side elevation of a simple chair without moving device swung to the rear,

Fig. 2 a side elevation of the chair frame, with moving device, in sitting position,

Fig. 3 the same view with another adjustment,

Fig. 4 a section on the line IV—IV of the chair Fig. 2,

Figs. 5 and 6 side and front elevation of the adjusting device,

Fig. 7 a perspective view of the air stirring device.

The rocking chair frame *a* rests upon supporting rollers *b* of the rigid frame *c*, provided on both sides of the chair. The foot rest *f* catches in the cogs *g* of the cranked lever *d*² and is therefore adjustable according to the size of the person using the same. The crank lever *d*, *d*² swings on an axis *d*¹ which lies in the chair frame *a* and is connected with a guide *e*, which turns on the axis *e*¹. If a person sitting in the rocking chair swings the hinged rods *d*, *e*, by means of the foot rest *f*, the frame *a* is brought into the position shown in Fig. 1. Just as easily as the backward swinging motion is possible, a return swing can again be produced by pressure of the lower legs upon the lever *d*².

For adjustment of the supporting position to the person using the chair, a movement of the seat upon the support is necessary. For this purpose the seat has a cog wheel *h* with crank *i*, by the turning of which the sector rack *h* and simultaneously the axle *h*¹ is turned. With the arms of the sector rack *h* a rod *i* is connected, which swings upon a rigid point on the frame *c*. By turning the cog wheel *h* therefore, the chair frame *a* is moved on the rollers *b* and the rocking motion transferred to the person seated in the chair. By means of the sector rack *h*, as indicated in Fig. 4, the movement of the

same is transferred to the other side of the chair where a corresponding lever *l* takes effect. It is therefore only necessary to turn a handle in order to move both sides of the chair simultaneously upon their supports.

The handle drive is indicated in Figs. 5 and 6. The handle *l* cannot directly be turned, as a peg *l'* catches in one of the holes of the rigid supporting part *p*. If 10 an adjustment is to be made, the handle *l* is first to be swung in opposition to the pressure of the spring *l''* around the peg *l'*, so that the pin *l'* emerges from the catch opening. Now the handle is turned until the 15 proper centre of gravity for the chair frame *a* is obtained, whereupon the pin *l'* is allowed to spring into the next opening *m*.

An extension wall *u* with blind-like openings is provided in the back rest of the 20 frame *a*, which former bears a frame consisting of cane or other light material and covered with canvas gauze or other light fabric. This frame consists of four flat parts *n*, *o* and *n'* *o'*, which come into contact with one another upon a cross bar *r*; but the frame has an opening at its lower 25 end on the right and left of this cross bar, which in each case is provided with a short wall *t*, *t'*. An easily movable disc *s* is provided on the cross bar *r*, the former, when 30 in motion, striking in the one case the wall *t* and in the other case the wall *t'*.

With the movement of the rocking chair the air penetrates alternately into the spaces 35 *w* or *w'* and also passes through the openings *q'* or *q* to the person seated in the chair. By means of the disc *s* the entrance to the opposite spaces is obstructed in each case, so that the air is always compelled by the 40 guidance of the canal caused between *t* or *t'* and the disc *s*, to discharge in the direction towards the person seated. When the chair moves forward in rocking, the air penetrates through the space *w'* and passes through the 45 canal *q* to the person seated. When the

chair is in backward motion the air penetrates through the space *w'*, throws back the disc *s* to obstruct the canal between *s* and *t*, and passes through the opening *q'* to the person seated.

If the rocking chair is at rest, an air current can be produced through the blind opening in the connecting wall *g*.

After thus having more fully described and ascertained the nature of my invention 55 and in what manner the same is to be performed, I declare that what I claim is:

1. A swing chair comprising seat, back and arm portions, a bell crank lever pivotally connected to the forward portion of said seat; a base for said chair having an upright rigidly secured thereto at one end, a second upright pivotally connected at its lower end thereto forwardly of said rigid upright and at its upper end pivotally connected with said bell crank, a roller secured to the free end of said rigid upright upon which said chair arm is adapted to move when pressure is applied to said bell crank. 60

2. A swing chair comprising seat, back, and arm portions, a bell crank lever pivotally connected to the forward portion of said seat: a base for said chair having an upright rigidly secured thereto at one end, a second upright pivotally connected at its lower end thereto forwardly of said rigid upright and at its upper end pivotally connected with said bell crank, a roller secured to the free end of said rigid upright upon which said chair arm is adapted to move when pressure is applied to said bell crank, 70 an arcuate segmental rack pivoted to said seat, a link connecting said rack and the upper end of said rigid upright and a gear having a crank secured to said arm and operatively engaging said rack for swingingly operating said chair. 75

In testimony whereof I have signed my name.

HERMANN SCHÖPS.
